VANITY BOX

Rudolph N. Houlihan, Bridgeport, Conn., assignor to The Bridgeport Metal Goods Manufacturing Company, Bridgeport, Conn., a corporation of Connecticut

Application December 13, 1937, Serial No. 179,437

12 Claims. (Cl. 132—82)

This invention relates to new and useful improvements in cosmetic holders and has particular relation to a vanity box.

An object of the invention is to provide a vanity box of neat and attractive appearance, and one in which the hinge between the cover and body is practically invisible and does not project beyond the walls of these parts.

Another object is to provide a vanity box wherein the parts may be individually finished and then assembled, no finishing operations being required on the assembled box.

A further object is to provide a box of a construction which can be easily assembled and with much less trouble than the usual constructions.

Other objects and advantages will become apparent from a consideration of the following detailed description taken in connection with the accompanying drawings wherein satisfactory embodiments of the invention are shown. However, it is to be understood that the invention is not limited to the details disclosed but includes all such variations and modifications as fall within the spirit of the invention and the scope of the appended claims.

In the drawings:

Fig. 1 is a front elevational view of my improved vanity box with parts broken away;

Fig. 2 is an enlarged sectional view therethrough, the view being taken substantially along the line 2—2 of Fig. 1;

Fig. 3 is a plan view of the body of the vanity box;

Fig. 4 is an edge elevational view of such body;

Fig. 5 is a plan view of the frame of the box, a portion being broken away;

Fig. 6 is a sectional view substantially along the line 6—6 of Fig. 5, a portion of a cover being shown;

Fig. 7 is a plan view of a powder receiving tray employed;

Fig. 8 is a sectional view on a reduced scale through said tray, a portion of a cover being shown associated therewith;

Fig. 9 is a sectional view through the body, the view being taken along the line 9—9 of Fig. 3;

Fig. 10 is an enlarged detail sectional view taken along the line 10—10 of Fig. 1 and showing the manner in which the main cover of the box is secured;

Fig. 11 is a somewhat similar view but suggesting the manner of assembling the cover with the frame and body;

Fig. 12 is an enlarged sectional view showing a

modified construction of cover, the view being through the center of a vanity box as suggested by the line 12—12 of Fig. 1;

Fig. 13 is a plan view showing the cover of Fig. 12 open;

Fig. 14 is a sectional view taken along the line 14—14 of Fig. 13;

Fig. 15 is a view partly in section and partly in elevation showing a spring clip for securing the mirror closed in the modified construction;

Fig. 16 is a top plan view of a somewhat different construction of box with my improved construction applied thereto and with a portion broken away to more clearly show the construction;

Fig. 17 is a front edge view of this box;

Fig. 18 is an end elevation thereof;

Figs. 19 and 20 are detailed sections on an enlarged scale substantially on line 19—19 and 20—20 of Fig. 16;

Fig. 21 is a plan view of a somewhat different construction of box in the opened position;

Fig. 22 is an end elevation thereof;

Fig. 23 is an elevation looking from the back of the box;

Fig. 24 is a back edge view of the cover removed from the box showing the hinge pin arrangement;

Fig. 25 is an edge view of the insert or body of the box showing the mounting for the hinge pin;

Fig. 26 is a detailed section on an enlarged scale taken substantially on line 26—26 of Fig. 23.

Referring in detail to the drawings and at first particularly to the form of the invention shown in Figs. 1 through 11 my improved vanity box includes a frame 11, a body 12 and a cover 13. Cover 13 may be ornamented or colored in any manner desired, or may be entirely free of ornamentation.

Frame 11 is generally rectangular and includes front and back portions or walls 14 and 15 and a pair of similar inverted U-shaped side portions 16 and 17. The frame is open through from top to bottom, and the inner arms 18 of the U-shaped portions define the sides of the opening. It is noted that such inner arms 18 (Fig. 6) are slightly shorter than the outer arms 19 of the U-shaped portions and that such inner arms stop short of the rear or back portion or wall 15 (Figs. 10 and 11).

For a purpose later to be described a catch 20 is mounted on the frame 11 and comprises a U-shaped spring member 21 arranged between the arms 18 and 19 of the U-shaped side portion 55

17 as best shown in Figs. 2 and 5. The wall 18 of such portion has a pair of slots therein and one end portion of spring member 21 carries a U-shaped part 22 the upper and lower arms of which extend through such slots (Fig. 2) to normally project at the inner side thereof. Obviously the part 22 may be pressed back into the channel of the U-shaped portion 17 by pressing inwardly with a thumb on the upper free edge thereof, but it will also be clear that spring member 21 is constantly urging the part 22 into projected position.

Body 12 is rectangular and includes a bottom wall 23, front and rear walls 24 and 25 and side walls 26 (Figs. 3, 4 and 9). The front and rear walls 24 and 25 have small nubs or lugs 27 struck up therefrom for a purpose to be set forth, and the front wall 24 also has a bead 28 formed to extend inwardly therefrom. As shown best in Fig. 4 the side walls 26 are substantially cut away between their end portions. On the upper edges of the end portions of the rear wall small inwardly curved lugs 29 are formed and such lugs provide nesting means for the engagement with and confining of the hinge pin 42 of cover 13 as will appear.

Body 12 is adapted to receive a tray 30 for the reception of powder either in loose or cake form. Such tray includes edge and bottom walls 31 and 32 of which one of the edge walls has a cover 33 hinged thereto as at 34. Such cover cooperates with a felt or other compressible sealing means 35 carried by a rectangular member 36 formed of sheet metal of angle cross section and having the felt 35 about the outer side thereof whereby when the member is within the tray the sealing material 35 is somewhat compressed between the upright portions of the angle member and the sides of the tray. Sufficient of the material is used so that it projects above the vertical portions of the angle member to be engaged and partly compressed by the cover 33 when the latter is in closed position.

When loose powder is placed in the tray 30 the sealing material 35 serves to prevent escape of the powder about the edges of the cover and in addition prevents the escape of the powder between the angle member 36 and the sides of the tray. Should the tray be supplied with powder in the form of a molded cake the cover 33 may be omitted, but when the cover is used the puff or other applicator for the powder may be disposed on the top or upper side of the cover when it is in closed position.

The main cover 13 is here shown as including a mirror 37 secured to the cover by having its edge portions received in a frame 38 which in turn has its edge portions confined within the inturned edge portions 39 of the sheet metal cover portion 40. Along its rear edge cover 13 is provided with a tubular portion 41 carrying a hinge pin 42 projecting beyond both side edges of the cover as shown in Figs. 1 and 6.

All the parts may be constructed as shown and given the desired finishing operations before the vanity box is assembled. In the assembly the cover 13 is inserted through the open frame 11 from the under side thereof and the extending ends of the hinge pin 42 are located in the U-shaped side portions 16 and 17 of the frame. That is, the projecting end portions of the hinge pin are passed inwardly of the frame across the short ends of the inner arms or walls 18 of the portions 16 and 17 as suggested in Fig. 11. Thus as the cover fills the space between such

portions 16 and 17 the hinge pin is completely concealed as will be seen from Figs. 6, 10 and 12.

Ordinarily the powder tray 30 is next inserted into the body through the lower open side thereof, but if preferred it may be inserted from the front either before or after the body 12 is inserted in the frame. The tray enters the body and is confined laterally by the inner walls 18 of the frame portions 16 and 17, and while the tray may thus have a friction fit its front and rear edges may be snapped under the nubs 27 to further serve as means preventing the tray falling from the body when the cover 13 is open. When the tray is within the body one of the edges of the tray is under the lower edge of catch part 22 and such catch part serves to maintain the tray cover 33 in closed position as in Fig. 2. Obviously part 22 may be pressed inwardly against the action of spring 21 when cover 33 is to be opened.

The body 12 is moved into the frame through the lower open side thereof. In this operation care is taken that the lugs 29 on the rear wall of the body enter the spaces between the walls 18 and 19 of the portions 16 and 17, and such lugs being curved at their upper or free ends as described and shown engage the projecting end portions of the hinge pin (see Fig. 10) and confine the same against the juncture of the rear wall 15 of the frame and the upper or connecting parts of the portions 16 and 17. In this way the cover is hinged to the box without the use of rivets or the like and in such manner that no hinge projects beyond the edges of the box as the hinge is completely concealed.

The body has a friction fit in the frame as the sides of the body engage the sides of the frame. If desired the frame may have the nubs or lugs 43 struck from the inner surface thereof in such manner as not to form openings therein and these nubs may serve to assist in maintaining the body in the frame. However, it will be apparent that there is no lancing etc. of the frame or other parts in such manner as to have any disfigurement show at the outer side of the vanity box. Further it will be clear that in the event any refinishing is to be done the box may be readily taken apart.

In the modification shown in Figs. 12 through 15 all of the structure including the mounting of the main cover on the box is the same as that of Figs. 1 through 11, the entire modification being concerned with the construction of the main cover of the box. The modified construction of cover generally designated 44 comprises a frame 45 secured in place by having its edges confined under the inturned edges 46 of the outer portion 47 of the cover. Frame 45 is of sheet metal, and when secured to the portion 47 defines a pair of compartments 48 and 49 at the under side of the cover. One of such compartments may receive rouge and the other an applicator therefor, or if desired each may receive a cosmetic and an applicator.

A frame 50 carrying a metal mirror 51 exposed at each of the front and back of such frame is hinged to frame 45 at 52. When the vanity is closed the mirror 51 constitutes a cover for the compartments 48 and 49, and considering such to be the closed position of mirror 51 it may be secured in closed position by means of a clip 53 located at the forward end of the frame 45. Such clip comprises a length of flat spring metal having its end portions bent to extend outwardly through the edge portions of frame 45 providing

spring fingers 54 adapted to clamp the mirror 51 in its closed position.

When the cover 44 is swung to open position the cover 33 is exposed and one side of mirror 51 is available for use. When the mirror is swung to open position as in Fig. 13 the other side thereof is exposed for use, and at this time the compartments 48 and 49 and their contents are available. As the mirror is closed its edges snap between the spring fingers 54, and the main cover carries a bead-like part 55 (Fig. 12) to engage with the bead 28 on the body 12 when the said main cover is in closed position whereby to retain it in such position against casual opening. 15 A thumb piece 56 facilitates lifting of the front edge of the cover for opening it.

In Figs. 16 to 20 inclusive is shown a slightly different construction of box involving the same arrangement for mounting the cover. This box 20 comprises a body member 57 having bottom, rear and front walls 58, 59 and 60 respectively, but open at its opposite end or side edges. Hinged to this body is a cover 61 which has a forward wall 62 extending down over the front wall 60 of the body. In this construction there are frame 25 members 63, although in this arrangement they are separate members and not connected by side walls as in the first form. The front, rear and bottom walls of the body however project beyond the side edges of the cover 61 and the frame 30 members 63 are cupped or U-shaped in cross section and are telescoped over these projecting walls of the body. The projecting portions of the rear wall 59 are curved inwardly at their 35 upper edges as shown at 64 to form seats for the projecting ends 65 of the hinge pin 66 which is mounted in a rolled over loop 67 formed in the rear edge of the cover 61. It will be seen from Figs. 16 and 19 that the cover may be assembled 40 to the body by seating the projecting ends 65 of the hinge pin in these nesting bearings 64 and then telescoping the frame members 63 over the projecting ends of the bodies. As will be seen from Figs. 16 and 19 the walls of these frame 45 members will hold the projecting ends of the hinge pin in these bearings 64 and thus the cover is hinged to the body. It will be seen that with this arrangement the hinge is entirely within the outline of the box the same as in the first form and no part of the hinge therefore projects beyond the box and the hinge is effectively concealed. The frictional action between the projecting ends of the body, walls and frame members 50 will retain the frame members in position. However, if a more permanent connection is required for the frame members they may be provided with small lugs 68 lanced inwardly from the walls of the frame member into openings 69 in the walls of the body. This box may be used for 55 different purposes, as vanity or to hold various articles, or it may have inserts (not shown) to hold a watch or other jewelry.

In the modification shown in Figs. 21 to 26 the same principle is used for mounting the hinged cover. In this construction the box 65 comprises a frame 70 in which is inserted a body 71 these two members having telescoping engagement. The body or insert 71 may provide a container for loose powder similar to the construction of Fig. 2. This body may be cupped to form a recess in which is inserted a rectangular member 72 formed of sheet metal of angle cross section similar to the member 36 of Fig. 2 forming a channel to receive a packing 73 cooperating 70 with a closure 74 hinged to the body at 75 to

retain the powder in the container, a spring catch 76 being provided to hold the closure in closed position. The box includes a cover 77 which may carry another powder container similar to the construction of Fig. 12, but as shown 5 it carries a mirror 78 held in the cover by a frame 79. The edge of the rear wall 80 of this cover is rolled inwardly as shown at 81 to hold a hinge pin or pins 82, and as this edge is rolled inwardly it will be seen it does not project outwardly beyond the surface of the wall 80. In this present arrangement instead of the end of the hinge pin or pins extending in a straight line from the ends of the loop in the cover they are bent downwardly and inwardly as indicated 15 at 83. The rear wall 84 of the body 71 is provided with grooves 85 pressed inwardly in the wall to receive these end portions 83 of the hinge pin and then this body 71 is telescoped within the frame 70. In this position the rear wall 86 of this 20 frame will lie over the open sides of these grooves 85 as shown in Fig. 26 and retain these free ends of the hinge pin in these grooves and thus pivotally secure the body to the cover of the box as in the other forms. To accommodate the 25 inwardly extending loop 81 of the cover the upper corner or edge of the body 71 may be recessed inwardly as shown at 87 to receive this loop 81. The hinge pin may be a single pin extending the full length of the loop 81 and having the free 30 ends 83, or if preferred it may comprise two short lengths bent to substantially U-shape. It will be seen from Fig. 26 the hinge does not project outwardly beyond the surface of the frame and therefore the hinge is effectively concealed and there is no projecting hinge as in the usual box construction. The frictional engagement between the body 71 and the frame 70 will retain these elements in telescoping engagement. However, if a more permanent connection 35 between them is desired lugs 88 may be lanced inwardly from the walls of the frame into openings or recesses in the body as described in connection with Figs. 16 to 20. A spring catch 89 may be provided on the body and frame cooperating 40 with the recess or notch 90 in the cover 45 to retain the cover in closed position.

As the present vanity body is put together without the use of rivets or other similar fastening means and without the use of a press or 50 the like, each part may be separately finished prior to the assembly and no finishing is required after the assembly of the parts. Further attention is called to the fact that no lancing or similar features are required to be used so as to 55 show at the outer side of the completed box, although such devices may be used if it is desired to more permanently secure the members together. Obviously either of the covers shown may be used since they are mounted in the same 60 way. In all forms shown the hinge between the cover and the body is completely concealed, and as there are no projections at the edges of the box, a very neat and attractive article is provided.

Having thus set forth the nature of my invention, what I claim is:

1. In a vanity box including a cover and a frame comprising hollow portions at each side edge of the cover, a hinge pin carried by the 70 cover and extending into each of said side portions, a body within said frame, and nesting means on said body and engaging and confining the extending portions of said pin against said frame portions.

2. In a vanity box, a frame including side, front and rear portions and top portions at the junctures of said side and rear portions, a body within the frame, a cover, a hinge pin carried by the cover and having its ends extending under said top portions whereby said ends are completely concealed, and nesting means carried by said body and confining the ends of said pin against the junctures of said top and rear portions of the frame.
3. In a vanity box, a frame having inverted U-shaped side portions the inner arm of each of which stops short of the rear part of the frame, a cover closing the space between said side portions, a hinge pin carried by said cover and extending at its ends into said portions across the ends of the short arms thereof, a body in said frame, and preformed nesting means on said body and engaging and confining the end portions of the hinge pin within said U-shaped frame portions.
4. In a vanity box, a rectangular frame having inverted U-shaped side portions the inner arms of which stop short of the rear of the frame, said portions having their outer and upper arms forming a closed corner with the rear of the frame, a cover closing the space between said side portions, a hinge pin on the cover and projecting beyond each side edge thereof and having its ends crossing the ends of the short arms of said inverted U-shaped portions and entering said closed corners, a body in the frame and including parts entering said inverted U-shaped portions through the open lower sides thereof, and means on such parts of the body and engaging and confining the ends of such hinge pin in said closed corners to hingedly mount the cover on the frame.
5. In a vanity box, a body, a cover for the body, a frame attached to said cover and forming a compartment at the under side thereof, means hinged to an end portion of said frame and adapted to be disposed over said compartment to close the same, a flat spring extending across the under side of said frame adjacent the end thereof opposite said hinge, and said spring having its ends bent and extending upwardly through the edge portions of said frame to engage the edges of said means to releasably secure it in position extending over said compartment.
6. In a vanity box, a rectangular frame having inverted U-shaped side portions, said portions having their outer and upper arms forming a closed corner with the rear of the frame, a cover closing the space between said side portions, a hinge pin on the cover and projecting beyond each side edge thereof and having its ends entering said closed corners, a body in the frame and including parts entering said inverted U-shaped portions through the open lower sides thereof, and curved lugs on the upper edges of such parts and comprising nesting means engaging and partly embracing such ends of the hinge pin and holding them against the junctures of the upper and rear walls forming such closed corners whereby the cover is hingedly mounted.
7. A vanity box comprising an open rectangular frame having opposite side portions of substantially inverted U-shape in cross section providing outer and inner spaced walls, a body having a bottom wall and side walls telescoping into the said outer walls of the frame, a holder for powder telescoping within the inner walls of the frame, and a hinged cover closing the upper side of the frame.
8. A vanity box comprising an open rectangular frame having opposite side portions of substantially inverted U-shape in cross section providing outer and inner spaced walls and top walls connecting them, a body having a bottom wall and also side walls telescoping into the said outer walls of the frame, a cover for the upper open side of the frame, a hinge pin for the cover projecting beyond said inner walls and lying against the said top walls, and means on the body forming seats for said pin on the opposite sides thereof from the top walls.
9. A vanity box comprising an open rectangular frame having opposite side portions of substantially inverted U-shape in cross section providing outer and inner spaced walls and top walls connecting them, a cover for the upper open side of the frame, a hinge pin for the cover projecting beyond said inner walls and positioned at the under side of said top walls, a body having a bottom wall and also having side walls telescoping into said outer walls of the frame, means on said body forming seats for said pin on the opposite side thereof from the top wall, and a powder container telescoping within the inner walls of the frame.
10. A box of the character described comprising a body, frame members at the opposite side edges of the body having telescoping engagement therewith, a cover, a hinge pin carried by the cover and extending at the opposite ends of the cover into said frame members, and said body being provided with nesting means to receive said ends and provide bearings therefor and confining said ends between said nesting means and a wall of the frame members.
11. A box of the character described comprising a body member having end portions provided with recesses, a cover for the body having a hinge pin projecting from the opposite ends thereof and seated in said recesses, and frame members telescoping over the end portions of the body and having walls retaining the pin in said recesses to connect the cover to the body.
12. A box of the character described comprising a body having recesses in a rear wall, a cover having a hinge comprising projecting pin portions seated in said recesses, and a frame members telescoping with the body and having walls extending over said recesses to retain the projecting pin portions therein to secure the cover to the body.

RUDOLPH N. HOULIHAN.
